BICYCLE STEERING POST

Carlton P. Pawsat, Maysville, Ky., assignor to Wald
Manufacturing Company, Inc., Maysville, Ky.

Filed Aug. 13, 1971, Ser. No. 171,794

Term of patent 14 years

Int. Cl. D12—11

U.S. Cl. D90—9

FIG-1

FIG-2

FIG-4

FIG-3

FIG-5

FIG. 1 is a side elevation view of a bicycle steering post showing my new design.

FIG. 2 is a front elevational view thereof as seen from the left side of FIG. 1.

FIG. 3 is a top plan view thereof.

FIG. 4 is a front elevational view of a modification of my design as seen from the left side of FIG. 1.

FIG. 5 is a top plan view of FIG. 4.

I claim:

The ornamental design for bicycle steering post, as shown and described.
